UNITED STATES PATENT OFFICE.

JAMES H. BURDETT, OF FLOSSMOOR, ILLINOIS.

DESIGN FOR A RACK.

Application filed November 21, 1927. Serial No. 24,224. Term of patent 7 years.

To all whom it may concern:

Be it known that I, JAMES H. BURDETT, a citizen of the United States, residing at Flossmoor, in the county of Cook and State of Illinois, have invented a new, original, and ornamental Design for Racks, of which the following is a specification, reference being had to the accompanying drawing, forming part thereof.

In these drawings—

Figure 1 is a front view of a rack showing my new design; and

Figure 2 is a plan view of the same.

As shown in the drawing, the panels represent openings through which seed packets or other devices to be displayed in the rack are inserted.

I claim:

The ornamental design for a rack as shown.

JAMES H. BURDETT.
